UNITED STATES PATENT OFFICE.

ANDREW B. LIPSEY, OF WEST HOBOKEN, NEW JERSEY.

GAS-BURNER.

SPECIFICATION forming part of Letters Patent No. 358,560, dated March 1, 1887.

Application filed March 31, 1886. Serial No. 197,285. (No model.)

To all whom it may concern:

Be it known that I, ANDREW B. LIPSEY, of West Hoboken, county of Hudson, State of New Jersey, have invented a certain new and 5 useful Improvement in Gas-Burners, of which the following is a specification.

My improvement consists in the combination of two or more obliquely-arranged gas-burner tips having gas-escape orifices arranged obliquely to their axes, and material capable of resisting heat arranged intermediate of the position occupied by flames issuing from the burner-tips. The gas will escape in such manner that when ignited the 15 flames will bend transversely toward each other, so as to meet or nearly meet at the edges. The flames will heat the intermediate air, and by rarefying it cause it to ascend. The adjacent atmosphere will flow to take the place 20 of the air which ascended after rarefaction, and thus the bending of the flames emanating from the burner-tips will be increased, and a circle or approximate circle of light will result.

25 In the accompanying drawings, Figure 1 is a side view of a gas fixture embodying my improvement and adapted to be fastened to the upturned or upwardly-extending end of a gas-supply pipe. Fig. 2 is a side view of another 30 gas-fixture embodying my improvement, but adapted for attachment to the lower end of a gas-supply pipe. Fig. 3 is a top view of part of a fixture, illustrating the manner in which flames emanating from the gas-burner tips 35 will be drawn around into circular form.

Similar letters of reference designate corresponding parts in all the figures.

In Fig. 1, A designates a body-piece adapted to be attached at the lower end to the upturned 40 end of or upwardly-extending end of a gas-supply pipe, B. This body-piece A may be secured to the gas-supply pipe B by screw-threads.

C designates gas-burner tips, of which there 45 may be any suitable number, although I have shown but two, inserted in a body-piece, A. They are represented as extending in reverse directions obliquely from the body-piece and

as having rounded ends provided with slots e, which are arranged to extend approximately 50 upward and obliquely to the axes of the tips. These tips may be fastened in place by screw-threads. They of course communicate with the interior of the body-piece.

Above the body-piece, Fig. 1, is a piece of 55 material, D, adapted to withstand the effects of heat produced by flames emanating from the gas-burner tips. It may be made of any suitable material—as, for instance, of metal or porcelain or like refractory material. It is represented as circular in form, and as flaring slightly from the lower end toward the upper end. It is shown as surrounding a rod, D', that is screwed into the body-piece, and has attached to its upper end a ring, E, whereby a shade, S, is 60 supported. Owing to the arrangement of the gas-escape orifices obliquely to the axes of the burner-tips the gas escaping from them is when ignited caused to bend laterally, so 65 that the sides of the flames will converge. 70 The flames will be so close to the piece D as to heat the latter very materially. Air in the immediate vicinity of the piece D will be rapidly heated and rarefied, so as to be caused to ascend. The air outside the flames has a tendency 75 to rush into the vacuum produced by the rarefaction of air around the piece D. Owing to this the tendency of the flames to bend around at their side edges toward each other is augmented, and a circle or approximate 80 circle of light is formed. A very desirable light is the result, as illumination may be had from it in all directions.

In Fig. 2 I have shown that the body-piece A may be closed at the lower end and secured 85 to the downwardly-turned or downwardly-extending end of a gas-supply pipe. The gas-supply pipe in this instance has the piece D fitted to it. Of course, if the piece D were omitted, the rod D' or the gas-supply pipe, 90 (shown in Fig. 2,) as the case might be, would constitute material capable of resisting the heat of flames issuing from the burner-tips. In this example of my improvement an additional benefit will result—namely, the heating 95 of the gas as it descends through the supply.

pipe B to the body-piece A. A ring, R, supporting a shade, S, is secured to the gas-supply pipe in this example of my invention.

What I claim as my invention, and desire

5 to secure by Letters Patent, is—

The combination of two or more obliquely-arranged gas-burner tips having gas-escape orifices arranged obliquely to their axes, and

material capable of resisting heat arranged intermediate of the positions which will be occupied by flames emanating from the gas-burner tips, substantially as specified.

ANDREW B. LIPSEY.
